ABSTRACT

A method for testing a thermal-responsive switch which utilizes liquidized nitrogen for lowering the switch to its operational level.

SWITCH TESTING APPARATUS

As is known, the testing of refrigerator and/or freezers at the manufacturing plant has been a rather time consuming operation, in that it has been necessary to operate the product until functional temperatures are achieved. In other words, a selective number of units are tested, being operated until the switch limits are reached and then it is determined whether or not the refrigerator and/or freezer is acceptable. A big drawback from the preceding, aside from time, was the fact that only a limited number of production units could be tested, because of either facility space and/or production rate. Accordingly, it has become necessary for consumer relations to furnish a workable product, where the pre-testing thereof can be readily accomplished and at a minimal cost.

The invention accomplishes all of the preceding objectives, i.e. rapid and limitless product testing and a savings in time and testing expense. Briefly, the invention utilizes a cryogenic gas, such as liquidized nitrogen, which is sprayed onto the appropriate switch in the refrigeration mechanism to reduce the temperature thereof to an operating level. Such may be accomplished through the use, typically, of a hand-controlled gun to spray the temperature responsive switch. As soon as the desired temperature level is achieved, the unit can be tested and determined whether or not it is satisfactory for sale.

The invention can be better understood from the following description, taken in conjunction with the accompanying drawing, wherein the single FIGURE thereof shows the components employed in the performance of the invention.

For the purposes of promoting a better understanding of the principles of the invention, reference will now be made to the embodiment illustrated in the drawing and specific language will be used to describe the same. It will nevertheless be understood that no limitation of the scope of the invention is thereby intended, such alterations and further modifications in the illustrated method, and such further applications of the principles of the invention being contemplated as would normally occur to one skilled in the art to which the invention relates.

Referring now to the figure, the method of the inven-

10 tion comprises the use of a source of liquidized nitrogen 12, a conventional regulator 14, and a spray gun 16 for achieving the direct depositing of the liquidized nitrogen onto a thermal-responsive switch 17 within a refrigerator and/or freezer 19. The process may be manually accomplished or, if desired, carried out through the use of a fixed equipment set-up. In use, the liquidized nitrogen is sprayed onto the switch, lowering the temperature of the switch to an operating level to permit operation of the refrigerator and/or freezer as after many hours of use.

15 In other words, the invention saves a considerable amount of time for lowering the temperature of the unit so that testing can be quickly accomplished. The switch testing is readily available for each product unit, serving to satisfy the manufacturer of the proper assembly of the product and readily reducing failures which commonly occur in a finished product.

20 While the use of liquidized nitrogen has been emphasized, other cryogenic gases may be employed, such as argon, oxygen, helium or hydrogen; however, nitrogen is most plentiful and is not expensive or potentially dangerous.

25 Thus, from the preceding, it should become apparent that the use of liquidized nitrogen effectively serves as a testing vehicle and, accordingly, represents a valuable contribution to product quality. The description hereabove should be considered illustrative and not as limiting the scope of the following claims:

30 I claim:

1. Apparatus for testing the operation of a thermostat mounted in a freezer or refrigerator comprising a source of a liquified nitrogen gas, means for pressurizing said source, an insulated flexible hose connected between said source and a gun, said gun including a nozzle for the delivery of a fluid stream therethrough and a solenoid operated valve for controlling the flow of said liquified gas through said hose to said nozzle, and a trigger for actuating the solenoid to open said valve.

35 2. The apparatus of claim 1 where a timer circuit is provided for closing said solenoid a predetermined time after operation of said trigger.
